UNITED STATES PATENT OFFICE.

ALVAH L. POWELL, OF MILES CITY, MONTANA, ASSIGNOR, BY MESNE ASSIGNMENTS, TO THE A. L. POWELL POWER COMPANY INCORPORATED, A CORPORATION OF MONTANA.

MECHANICAL MOVEMENT.

Application filed December 10, 1919, Serial No. 343,958. Renewed November 9, 1923.

To all whom it may concern:

Be it known that I, ALVAH L. POWELL, a citizen of the United States, a resident of Miles City, in the county of Custer and

5 State of Montana, have invented a certain new and useful Improvement in Mechanical Movements, of which the following is a full, clear, and exact description, such as will enable others skilled in the art to which it applies 10 to make and use the same, reference being had to the accompanying drawings, forming part of this specification.

This invention relates to certain new and useful improvements in mechanical movements and relates more to that particular line of power transmitting mechanisms known in the art as planetary gearing. Some of the principles embodied in this application are suggested in my co-pending applications 107,308 and 142,664 reference being had to Fig. 7.

The principal object of the present invention is the novel manner in which the force of power is transmitted from a drive shaft 25 to a driven element by means of orbital moving elements disposed between the drive shaft and the driven element.

Another object of the present invention is the provision of a driven element which is 30 rotatably suspended upon the enclosed casing.

Another object of the invention resides in the novel manner in which the driven element is balanced by disposing to either side 35 thereof and in gear therewith the intermediate power transmitting gear or gears.

While I have set forth above some of the objects of the present invention it will, of course, be understood that others will present 40 themselves to those skilled in the art after reading the following specification in connection with the attached drawings wherein I have shown merely for the purpose of illustration the preferred embodiments of the same.

In the drawings Fig. 1 is a transverse section illustrating a form employing peripheral gearing; Fig. 2 is a vertical section taken on lines 2-2 Fig. 1; Fig. 3 is a cross 50 sectional view of the driven element; Fig. 4 is a view similar to Fig. 1 but in this instance using frictional contact between the various elements; Fig. 5 is a perspective view of a modified form in keeping with the 55 principles set forth in the foregoing views;

Fig. 6 is a vertical section of the type of drive illustrated in Fig. 5; and Fig. 7 is a detailed view of a slightly modified nature from that of Fig. 6.

Referring more in detail to the drawings 60 wherein similar letters of reference indicate corresponding parts, and referring more particularly to Figs. 1 and 4 I have shown a casing 1 which is rigidly supported and has its intermediate portion removed so that the 65 same presents two substantially cup-shaped enclosures, the inner ends of which are arranged toward each other. Transversely journaled through the center of these casings is a drive shaft 2 having keyed thereupon a 70 drive pulley 3 which is connected by any suitable means to the power producing mechanism. Also keyed to the shaft 2 are pinions 4-4 which are arranged within the casing 1. The inner walls of the casing 1 75 adjacent their open ends are provided with racked teeth indicated at 5-5. Interposed between the pinion 4 on the drive shaft and the racked teeth 5-5 on the casing is a gearing 6-6. This gearing is adapted to mesh 80 with the teeth in pinion 4 and also the racked teeth on the casing 1 which results in the orbital movement of the gears 6 about the shaft 2 and at the same time independent rotation about their own axis. Each of the 85 gears 6 are provided with secondary gear teeth 7 which are adapted to co-act with one of the racked faces 8 of a driven element 9. This driven element is suspended toward the open ends of the casing 1 upon rims 10-10 90 and in order to reduce the frictional engagement between the suspended element 9 and the casing 1 I provide anti-friction bearings indicated at 11-11.

In order that gears 6 be held in their 95 proper position within the casing 1, each of said gears is peripherally slotted as indicated at 12 and into each slot an inwardly projecting rib or flange is arranged to extend. The casing 1 as well as the pinion 4 100 is provided with these flanges 13. The outer face of the driven element 9 is provided with gear teeth in the form shown in Fig. 1 and by which the power may be taken off of the same by a geared pinion or the like. 105

In the form illustrated in Fig. 4 I rely solely on frictional contact between the various parts to transmit the power from the drive shaft 2 to the driven element 9 and in this case the peripheral portion of the ele- 110

ment 9 may be smooth or uninterrupted so that power may be taken therefrom by any suitable form of belt or the like.

Referring more particularly to the illustrations of Figs. 5, 6, and 7, it will be noticed that in these cases I provide an aligned drive and driven shaft, 14 indicating drive shaft and 15 the driven shaft. An open-ended casing illustrated at 16 is rigidly supported and has transversely journaled therein the drive shaft 14. This drive shaft 14 has keyed to it a pinion 17 which is suitably geared and also provided with a circular ridge or flange 18. The casing 16 is provided with an internal rack indicated at 19 and also an inwardly extending portion 20 in alignment with the flange of the pinion 17. Interposed between the pinion 17 and the internal rack 19 and in mesh therewith is a gear 21 which gear is also provided with gear teeth indicated at 22. The driven shaft 15 is supported in axial alignment with the drive shaft by a standard or bracket 23. Keyed to the shaft 15 is a pulley 24 one side of which is preferably of an open nature and geared or racked as indicated at 25. This rack is adapted to mesh with the secondary gears on the gear 21. The pulley 24 may be geared as shown or if desired the power therefrom may be taken by a belt in which case the periphery would be smooth somewhat as suggested in Fig. 4. The gears 21 are provided with peripheral recesses as suggested in the foregoing figures and into these recesses the flanges or ridges 18 and 20 on the pinion and casing respectively are adapted to extend thereby suspending the gears 21 in their proper working position.

In the modified form shown in Fig. 7 the pulley 24 may be provided with an inwardly extending tongue 25 which is adapted to enter into a recess 26 peripherally arranged within the gear 21.

Briefly described the operation of the mechanism is as follows:—Power being applied to the shaft 2 revolves the pinions 4 and causes the gears 6 to travel in an orbital path about the shaft 2; each of the gears will also be caused to rotate about their own axis, owing to the intergearing between the same and the stationary casing. These gears 6 are co-operatively arranged so as to communicate their peculiar cycle of movement to the driven element 9.

While I have described in the foregoing the preferred embodiments of the invention it will, of course, be understood that certain

variations therefrom may be resorted to without sacrificing any of the spirit of the invention and the scope of protection contemplated will appear from the claims.

What I claim is:—

1. In a power transmitting mechanism comprising a casing, a drive element arranged concentrically within the casing, gears disposed between and coactive with the drive element and the wall of the casing, means extending from the wall of the casing and the drive element and engageable with the gears to hold the said gears against lateral displacement in both directions, and a driven element operatively associated with the gears.

2. In a power transmitting mechanism comprising a casing having an inwardly directed flange, a drive element arranged concentrically within the casing, said element provided with a peripheral flange, gears disposed between and coactive with the drive element and the wall of the casing and each gear having a slot within its periphery for the reception of the respective flanges on the wall of the casing and the drive element for maintaining the gears in position, and a driven element operatively associated with the gears.

3. In a gearing of the class described comprising a stationary casing having an internal rack and an inwardly directed flange, a drive shaft journaled within the casing and having a drive pinion thereon, said pinion having a peripheral flange, a gear interposed between the rack of the casing and the drive pinion and provided with a peripheral slot for the reception of the respective flanges on the casing and the drive pinion for maintaining the gear in operative position, and a driven element operatively associated with said gear.

4. In a power transmitting mechanism comprising a casing, a drive element arranged within the casing, gears disposed between and coactive with the drive element and a wall of the casing, peripheral interfitting means between the gears intermediate the sides thereof and the casing and drive element for holding the said gears against lateral movement in either direction, and a driven element operatively associated with said gears.

In testimony whereof I hereunto affix my signature, this 10th day of December, 1919.

ALVAH L. POWELL.
